JEAN V. GIESLER, OF KNOXVILLE, TENNESSEE, ASSIGNOR, BY MESNE ASSIGNMENTS, TO THE FULTON SYLPHON COMPANY, OF KNOXVILLE, TENNESSEE, A CORPORATION OF DELAWARE

THERMOSTATICALLY-CONTROLLED VALVE UNIT

Application filed January 28, 1937. Serial No. 164,358.

This invention relates to thermostatically operated valve mechanism, and particularly to thermostatically operated valve mechanism for regulating the circulation of the cooling medium through the cooling system of an internal combustion engine. The invention is capable of embodiment in thermostatically operated valve mechanism both of the choker type, wherein the position of the valve member determines the quantity of cooling medium circulating through the cooling system, and of the by-pass type, wherein the position of the valve member determines the path of the cooling medium circulating through the cooling system.

With the increase in use of thermostatically operated valve mechanism for controlling the circulation of the cooling medium through the cooling systems of automobile engines, particularly of the medium priced and lower priced cars, there is an increasing demand for thermostatically operated valve mechanism which constitutes a self-contained unit, and which is composed of a minimum number of parts, so that it is simple and inexpensive to manufacture and install.

It is an object of this invention to provide a device of the character described which is composed of a minimum number of simple parts which may be produced at a minimum expense and wherein the support for the thermostat may be formed as an integral unit.

Another object of this invention is to provide a device of the character described wherein the valve seat, and also preferably a mounting ring for the unit, may also be formed integrally with and form a unitary part of the unitary support for the thermostat.

Another object of this invention is to provide a device of the character described wherein the thermostat support is formed as an integral unit and so constructed that the thermostat may be assembled therewith from a lateral direction, so as to facilitate the assembly of the thermostat therewith.

Another object of this invention is to provide a device of the character described wherein the thermostat support is formed as

an integral unit and so constructed that the thermostat may be installed therein from a lateral direction and wherein the valve member may be readily assembled therewith for cooperation with a valve seat formed integrally with said support.

Other objects will appear as the description of the invention proceeds.

The invention is capable of receiving a variety of mechanical expressions, two of which are shown on the accompanying drawings, but it is to be expressly understood that the drawings are for purposes of illustration only and are not to be construed as a definition of the limits of the invention, reference being had to the appended claims for that purpose.

Referring in detail to the drawings, wherein the same reference characters are employed to designate corresponding parts in the several figures,

Fig. 1 is an axial section of an embodiment of the present invention;

Fig. 2 is a side view of the embodiment of Fig. 1;

Fig. 3 is an end view of said embodiment taken from the valve end of the unit;

Fig. 4 is an end view of said embodiment taken from the opposite end of the unit;

Fig. 5 is an elevation, partly in longitudinal section, of another embodiment of the present invention; and

Fig. 6 is an end view of the embodiment of Fig. 5.

In the form shown in Figs. 1 to 4 inclusive, the thermostat 10 is illustrated as composed of a stationary end wall 11 and a movable end wall 12 suitably attached, as by soldering or brazing, to a deeply-corrugated, flexible, tubular wall 13, preferably of resilient metal, and forming therewith a closed chamber which is designed to receive a volatile fluid of any suitable character. The stationary end wall 11 is shown as provided with a boss 14, threaded or otherwise suitably formed for attachment to a support as hereinafter described, said boss 14 desirably containing the filling opening 16, which may be sealed by a stopper 17 and solder 18. The movable end wall 12 is shown as provided with an inwardly directed boss 19 to receive

a threaded recess 20, which preferably does not extend through said boss, said end wall 12 also having an outwardly projecting annular boss 21. Internally, said thermostat is shown as provided with a tubular stop member 22 which may be mounted on the boss 19, although it may be mounted on the stationary end wall 11 if desired, to limit the collapse of the thermostat when the same is not mounted in operative relation with the valve member and its seat.

In conformity with the present invention a support for the thermostat is provided as an integral unit, said support also preferably having formed integrally therewith a seat for the valve member and also if desired means for mounting the unit in operative position, and said support also preferably acting as a guide and a limit stop for the expansive and contractive movements of the thermostat. Said support is shown as formed as an open generally rectangular frame composed of a pair of leg members 23, preferably parallel and spaced by a distance somewhat greater than the outside diameter of the thermostat, and a pair of transverse members 24 and 25, integral with said leg members 23 and preferably extending at right angles thereto adjacent the opposite extremities thereof. Said transverse members 24 and 25 may take a variety of forms. In the embodiment shown in Figs. 1 to 4, the transverse member 24 takes the form of a strut of a width somewhat greater than the diameter of the threaded boss 14, and is provided with a threaded aperture 26 to receive said boss. Member 25 is illustrated as a spider having a central hub 27 provided with an aperture 28 therethrough, although it may take the form of a strut or have any other suitable form.

Formed integrally with the thermostat support is a valve seat ring 29 which provides a central valve opening 30. Ring 29 may be in the same plane as or in a different plane from the transverse member 25, and if the guide and stop afforded by said member 25 are not desired, it may take the place of said member in forming the fourth side of the generally rectangular integral frame. Also preferably formed integrally with said support is a mounting ring 31. In the form shown in Figs. 1 to 4, the valve seat ring 25 and the mounting ring 31 are provided at opposite ends of the support, although this is not essential, as for some forms of units the mounting ring may be formed at the same end of the support as the valve seat ring, or constitute an extension of the valve seat ring. In this embodiment the valve end of the support is also provided with a surrounding annular portion 32 formed integrally therewith, and constituting a bearing ring for the valve end of said support when the latter is mounted in operative position in a cooling system.

The free distance between the transverse members 24 and 25 is made at least as great as the overall length of the thermostat when in contracted position so that the thermostat may be mounted in position by insertion laterally into the opening afforded by said rectangular frame. Preferably the transverse member 25 is designed to act as a stop for limiting the expansive movement of the thermostat, the central hub 27 being shown as adapted to engage and stop the annular boss 21 on the movable end wall of the thermostat, and in this event the extent of projection of the threaded boss 14 from the stationary end wall 11 must be no greater than the intended stroke of the thermostat so that the overall length of the thermostat shall not exceed the distance between said transverse members 24 and 25.

The valve stem and valve member may be attached to the movable end wall 12 of the thermostat in any suitable way. In the form shown, the valve member 33 is illustrated as integral with the valve stem 34, although if desired the valve member may be formed separately from and attached to said valve stem 34. The inner end of the valve stem is threaded for engagement in the threaded recess 20 and may be locked therein in any suitable way, as by a pin 35 passed through openings drilled in the annular boss 21 and the valve stem 34.

The thermostat support, together with the valve seat ring and mounting ring integral therewith when used, are preferably made of cast metal and cast as a unit. If desired, the apertures 26 and 28 may be drilled in the casting, or suitable openings may be left in the casting as made. The aperture 26 may thereafter be tapped to provide the screw thread 26, or any other suitable means for attaching the stationary end wall 11 of the thermostat to the member 24 may be provided. If found desirable, the face of the valve seat ring 29 may be ground to provide a proper seat for the valve member 33 and the ring 31 may be machined to proper size, if necessary.

The thermostat is assembled with the support by introducing the same laterally into the rectangular opening afforded in the frame between the legs 23 and the transverse members 24 and 25, and the boss 14 may then be threaded into the aperture 26 or otherwise suitably attached to the transverse member 24. The valve stem 34, either with or without the valve member 33 thereon, may then be passed through the aperture 28 in the transverse member 25 and threaded into the recess 20 or otherwise suitably secured to the movable end wall 12 of the thermostat. A hole may then be drilled through the annular boss 21 and valve stem 34 to receive the pin 35 by which, said stem is locked against displacement or said stem may be otherwise suitably

locked to said movable end wall. The valve member should be so related to the movable end wall 12 of the thermostat that when the valve member is in contact with its seat the 5 internal stop 22, when used, is out of contact with the stationary end wall 11 of said thermostat.

In the embodiment of Figs. 5 and 6, a simpler construction is illustrated wherein 10 the thermostat support takes the form of a U-shaped frame having legs 40 and transverse member 41. Formed integrally with said frame is a ring 42 and a transverse member 43, shown as connecting the legs of the frame 15 adjacent their junction with the ring 42, but spaced from said ring. Ring 42 projects radially outside of the frame sufficiently to constitute a mounting ring for the unit, and also 20 functions as the valve seat for the valve member 33. The transverse member 43 is enlarged or otherwise suitably formed intermediate its length so as to provide a hub 44 apertured to receive the valve stem 34. Otherwise the construction and manner of 25 assembly of the parts in the embodiment of Figs. 5 and 6 is the same as heretofore described in conjunction with the embodiment of Figs. 1 to 4 inclusive.

It will therefore be perceived that a thermostatically operated valve unit has been provided which is composed of a minimum number of parts, including a support which is formed as an integral unit, a thermostat, and a valve stem and valve member which may 30 also be formed as a unit, while the valve seat and mounting ring may also be formed integrally with and constitute a unitary part of the support. The thermostat may be assembled with the support by movement into 35 the opening of the frame thereof from a lateral direction, and then be threaded or otherwise fixedly attached to the support without using any of the more or less expensive and complicated attachments heretofore employed, while the valve stem and valve member 40 may also be readily assembled with the thermostat and support after the thermostat is in position. The unit is therefore simple and inexpensive to manufacture and assemble, and may be produced at a minimum expense.

When assembled the thermostat is fixedly and rigidly retained against displacement with its stationary end wall secured to the 45 thermostat support and with its movable end wall attached to the valve member, and the thermostat support cooperates with the valve stem to guide the thermostat in its expansive and contractive movements, and also preferably limits the extent of such movements.

While the embodiments of the invention illustrated on the drawings have been described with considerable particularity, it is to be expressly understood that the invention is not restricted thereto, as the same is capable

of receiving other mechanical expressions, some of which will now readily suggest themselves to those skilled in the art, while changes may be made in the details of construction, arrangement and proportion of parts without departing from the spirit of this invention. It is to be expressly understood that the details of the thermostat form no part of the present invention and that other suitable forms of thermostat than that illustrated may be used while other suitable forms of attachment of the stationary end wall of the thermostat to its support and of the valve stem to the movable end wall of the thermostat may be employed, without departing from the spirit of this invention. Reference is therefore to be had to the claims hereto appended for a definition of the limits of the invention.

What is claimed is:

1. In a thermostatically operated valve unit, in combination with a thermostat, a thermostat support forming a complete integral generally rectangular frame with which the thermostat may be assembled by lateral movement through the opening thereof, and means whereby the thermostat may be fixedly attached to one of the sides of the complete frame, the opposite side of said frame being provided with a valve seat and with guiding means for the expansive and contractive movements of the thermostat.

2. In a thermostatically operated valve unit, in combination with a thermostat, a thermostat forming a complete integral generally rectangular frame with which said thermostat may be assembled by lateral movement through the opening thereof, means for attaching said thermostat to one side of the complete frame, and a valve stem attachable to said thermostat after the thermostat has been assembled with said frame, one side of said frame being provided with a valve seat and having an opening for guiding said stem and through which said stem may be introduced for attachment to said thermostat.

3. In a thermostatically operated valve unit, in combination with a thermostat, a thermostat support composed of a complete cast metal generally rectangular frame having openings in opposed members whereby said thermostat may be attached to one of said members and a valve stem passed through the other of said members into position for attachment to said thermostat, and a valve seat member cast integral with the opposite side of said frame from that to which said thermostat is attached, said valve seat being on the exterior of said frame.

4. In a thermostatically operated valve unit, in combination with a thermostat, a thermostat support composed of a complete cast metal generally rectangular frame having openings in opposed members whereby said thermostat may be attached within the frame to one of said members and a valve stem

passed through the other of said members into position for attachment to said thermostat, and a mounting member cast integral with the side of said frame to which the thermostat is attached and projecting peripherally therefrom.

5. In a thermostatically operated valve unit, in combination with a thermostat, a combined thermostat support and valve seat member forming a complete integral generally rectangular frame with which the thermostat may be assembled by lateral movement through the opening thereof, and means whereby the thermostat may be fixedly attached to said frame after insertion laterally through the rectangular opening thereof. 75

6. In a thermostatically operated valve unit, in combination with a thermostat, a combined thermostat support and valve seat member forming a complete integral generally rectangular frame with which the thermostat may be assembled by lateral movement through the opening thereof, and means whereby the thermostat may be fixedly attached to said frame, the opposite side of said frame being provided with means for guiding the expansive and contractive movements of the thermostat and with an integral ring forming said valve seat member. 80

7. In a thermostatically operated valve unit, in combination with a thermostat, a combined thermostat support and valve seat member forming a complete, open, generally rectangular frame with which the thermostat may be assembled by lateral movement through the opening thereof, means for attaching said thermostat to said frame, the opposite side of said frame having a guide opening therein, and a valve stem attachable to said thermostat through said opening. 95

8. In a thermostatically operated valve unit, in combination with a thermostat, a combined thermostat support and valve seat member formed of cast metal and including a pair of leg members and a pair of transverse members integral therewith and forming a complete frame, said thermostat being laterally insertible into said support through the opening afforded by said leg members and transverse members, a valve stem attached to said thermostat, and means for attaching said thermostat to one of said transverse members, the opposite transverse member cooperating with said valve stem to guide the movement of the thermostat. 100 110

9. In a thermostatically operated valve unit, in combination with a thermostat, a valve stem, a one-piece support for said thermostat comprising a pair of leg members, a pair of transverse members integral with said leg members and forming a complete open rectangular frame, one of said transverse members having a guide opening for the valve stem and the other of said transverse members having means for attaching the thermo- 115 120 125

stat, and a mounting ring integral with said last named transverse member.

In testimony whereof I have signed this specification.
